A. J. H. KOK.
REVERSING GEARING.
APPLICATION FILED JAN. 14, 1919.

1,357,712.

Patented Nov. 2, 1920.

UNITED STATES PATENT OFFICE.

AUGUST J. H. KOK, OF DELFT, ZUID, NETHERLANDS.

REVERSING-GEARING.

1,357,712.

Specification of Letters Patent.

Patented Nov. 2, 1920.

Application filed January 14, 1919. Serial No. 271,058.

To all whom it may concern:

Be it known that I, AUGUST J. H. KOK, a subject of the Queen of the Netherlands, residing at Delft, Zuid, Netherlands, have 5 invented certain new and useful Improvements in Reversing-Gearing; and I do hereby declare the following to be a full, clear, and exact description of the invention, such as will enable others skilled in the art to 10 which it appertains to make and use the same.

This invention relates to lathes, and more particularly to an improvement in the operating gearing for rotating the head stock 15 for turning the work.

The primary object of the invention is to provide simple and efficient gearing which is compactly arranged so as to occupy a minimum of space by means of which the 20 head stock of the lathe may be readily rotated in either direction at any desired speed.

A further object is to provide novel and efficient means for reversing the direction 25 of rotation of the head stock, friction clutches being employed so as to reduce danger of breakage to a minimum.

Another object is to provide means whereby the head stock may be rotated from an 30 electric motor or other suitable source of power, this means being adjustable so as to cause rotation of the stock at any desired speed.

Further objects will appear from the detailed description.

In the drawings:

Figure 1 is a fragmentary side view of a lathe of conventional construction showing a gearing constructed in accordance with 40 my invention applied.

Fig. 2 is a detail of the clutch shifter.

Fig. 3 is a detail of the same and the holding springs therefor.

Fig. 4 is a fragmentary detail section of 45 one of the clutches and the means for normally holding the same in inoperative position.

Fig. 5 is a fragmentary side view showing a modified form of driving connection.

The lathe frame designated generally by A may be of any suitable or standard construction and supports a bed 1 provided adjacent one end with the spaced uprights 2 which rotatably support a stub shaft 3 carrying at its inner end the head stock or disk 4 for holding the work. Inwardly directed bevel-gears 5 are mounted for free rotation

on stub shaft 3 between the uprights 2 and mesh with a bevel-pinion 6 secured on the upper end of a vertical shaft 7 rotatable through bed 1, the lower end of this shaft being seated in a socket 8 carried by bracket 9 secured to the adjacent supporting upright or leg 10 of the lathe frame. By operatively connecting either one of the gears 5 to the stub shaft 3, optionally, the head stock 4 may be rotated in either direction desired.

Each of the gears 5 is provided with a conical socket 11 in its inner face which is adapted to receive a cone clutch member 12 mounted adjacent thereto and feathered on the shaft 3 for rotation therewith. A shifter indicated generally by 13 is mounted between the clutch members 12 on shaft 3 for movement longitudinally thereof in either direction. This shifter comprises an outer annular member 14 provided with the diametrically opposite radially projecting arms 15, and an inner ring 16 mounted concentric with the annular member 14 and co-operating therewith to form a raceway for bearing balls 17 which project beyond the opposite sides of the shifter as in Fig. 1. The outer end portion of each arm 15 is provided with an axial bore which receives the inner end portion of a short rod 18 provided at its outer end with a handle 19, the rod being mounted so as to be readily turned in arm 15, as indicated in Fig. 2. This handle 19 is provided with an extension or shoulder 20 which is adapted to be moved into engagement with either one of two leaf springs 21 carried by a supporting bracket 22 secured to the bed 1, the shoulder 20 acting as a cam to move the shifter in the desired direction. By turning the handle 19 into horizontal position so as to bring the member 20 into contact with one of the springs, as in Fig. 1, the shifter will be moved into engagement with the left hand cone 12 as considered from this figure, thus forcing this cone into the socket of the adjacent bevel-gear 5 so as to cause rotation of stub shaft 3. By turning the handle 95 through an arc of 180° so as to bring member 20 into engagement with the other cone, the other cone is moved into engagement with its co-operating clutch thus readily reversing the direction of rotation of the shaft 3 and head stock 4. The springs 100 21 may be adjusted toward or away from each other by means of an adjusting screw 23 threaded therethrough, and these springs are of arcuate or bowed shape for fitting

about the arcuate outer end of the member 20, thus insuring that the shifter will be held properly in adjustment. When the shifter is in an intermediate or inoperative position, the handle 19 is disposed vertically, and the cones are held out of engagement with the gears by means of a device such as illustrated in Fig. 4. Each cone is provided with a bore extending there-through which receives a plunger 24 provided at its inner end with a head 25 which is forced into engagement with the gear 5 at the inner end of socket 11 by means of an expansion coil spring 26 mounted about the plunger and confined between head 25 thereof and a nipple 27 screwed into the outer end portion of the bore which receives the plunger, inward movement of the plunger being positively limited by jam nuts 28 screwed upon the outer end portion of the stem thereof. The plunger acts to move the cone clutch member out of engagement with its coöperating gear when the shifter is moved into inoperative position, the cone being normally maintained in this position by the plunger and associated parts.

A face disk 29 is mounted on shaft 7 and is connected thereto by pin and slot connections, as at 30, so as to rotate with the shaft 30 and have movement longitudinally thereof. A short flanged sleeve 31 is slidably mounted on shaft 7 with its upper end in engagement with the collar of disk 29, this sleeve being normally forced upwardly by an expansion coil spring 32 mounted about the shaft and confined between the sleeve and an adjusting wheel or disk 33 screwed upon the shaft. The spring acts to normally hold the disk in engagement with a wheel disk 34 which is secured upon the squared end of a tubular shaft 35 rotatable in a bearing collar carried by a hanger 36 depending from a screw shaft 37 rotatable in brackets 38 carried by frame A, a suitable hand wheel 39 being provided at one end of this shaft for rotating the same. The tubular shaft 35 is provided with a longitudinally extending slot 40 which receives a pin or screw 41 secured in an armature shaft 42 of an electric motor 43 which is mounted in axial alinement with shaft 35. By this arrangement, the disk wheel 34 may be rotated from the motor shaft, and this disk wheel may be adjusted by means of the screw shaft 37 and the hanger 36 across the face of disk 29 so as to vary the speed of rotation thereof thus permitting accurate control of the speed of rotation of the head stock 4. Where practicable, or if desirable, the motor may be mounted upon suitable supporting rails 44 for sliding movement thereon, the disk 34 being secured directly upon the armature shaft of the motor, as in Fig. 5. This eliminates the tubular sleeve 35 and associated parts, the motor shaft being, together with

the motor, shifted by means of the hanger 36 and screw shaft 37. If desired, though not necessarily, a compound spur gear wheel 45 may be mounted upon shaft 7 so as to permit the shaft to be driven positively 70 from a driving gear carried by a drive shaft for obtaining a positive drive in cases where the friction drive is found undesirable.

It will be evident that there may be slight changes made in the construction and arrangement of the details of my invention without departing from the field and scope of the same, and I intend to include all such variations, as fall within the scope of the appended claims, in this application in 80 which a preferred form only of my invention is disclosed.

What I claim is:

1. In a lathe, a rotatably mounted stub shaft, opposed bevel-gears mounted on said shaft for independent rotation thereon, each of said gears being provided with a conical socket in its inner face, cone clutch members mounted on the shaft adjacent the inner faces of the respective gears, a shifter slidably mounted on the shaft between said clutch members, said shifter being provided with outwardly projecting arms, rods mounted in said arms for free rotation therein, abutment members carried by said rods, and resilient members rigidly supported at opposite sides of each of said arms and positioned for engagement by said abutment member for moving the shifter in either direction when the rods are turned in proper direction for moving either one of said cone clutches, optionally, into operative engagement with its corresponding gear, and means for simultaneously rotating said gears in opposite directions. 105

2. In a lathe, a rotatably mounted shaft, gears rotatably mounted on said shaft for independent rotation thereon, clutch members mounted on the shaft adjacent the gears, a shifter slidably mounted on the shaft between the clutch members, said shifter being provided with outwardly projecting arms, rods rotatably connected with said arms, abutment members carried by said rods, and resilient members rigidly mounted upon opposite sides of each of said arms and positioned for engagement by said abutment member for moving the shifter in either direction when the rods are turned in proper direction for moving a selected one of said clutches into operative engagement with its corresponding gear, and means for rotating the gears in opposite direction. 110

In testimony whereof I affix my signature in presence of two witnesses.

AUGUST J. H. KOK.
